UNITED STATES PATENT OFFICE.

STEPHEN G. SKINNER, OF WILMETTE, ILLINOIS.

APPARATUS FOR COMPRESSING AIR.

1,119,889.

Specification of Letters Patent.

Patented Dec. 8, 1914.

Application filed April 15, 1913. Serial No. 761,276.

To all whom it may concern:

Be it known that I, STEPHEN G. SKINNER, a citizen of the United States, residing at Wilmette, in the county of Cook and State 5 of Illinois, have invented a certain new and useful Improvement in Apparatus for Compressing Air, of which the following is a full, clear, concise, and exact description, reference being had to the accompanying 10 drawings, forming a part of this specification.

My invention relates to apparatus for compressing air and the object of my invention is to provide a device for that purpose 15 which itself is operated by air compression, so that it may be applied to an otherwise idle cylinder of an internal combustion engine and be operated by the air compressed by the piston in said cylinder.

20 The device of my invention is particularly adapted for use in the automobile industry, since it may be employed for pumping up tires and may be operated automatically by merely substituting it for one of 25 the spark plugs in an automobile internal combustion engine.

Structurally, the device of my invention 30 comprises a cylinder, preferably of uniform diameter throughout its length, within 35 which is disposed a pair of connected pistons which are adapted to reciprocate within the cylinder. Located between the two pistons is a chamber, which may be termed the "compression chamber." Disposed 40 within this chamber is a stationary piston carried by the wall of the main cylinder of the pump. A suitable connection which 45 may be screwed into the spark plug opening of an automobile is provided in order that 50 the bottom of the lower piston may be subjected to the compression formed in the engine cylinder. The connected pistons are moved intermittently in one direction by the compression formed in the engine cylinder, while the return movement of the pistons is secured by the suction produced by 55 the piston in the engine cylinder, the air cushion which is formed in the top of the pump cylinder and whatever effect gravity 50 may have. A valved passage is provided for passing air from below the lower one of the movable pistons to the chamber between the movable pistons and above the stationary piston therein during the upward movement of the connected pistons. This air 55 above the stationary piston whose pressure

has been raised above ordinary air pressure by the engine piston, is adapted to pass around the stationary piston when the movable pump pistons are returned upon the 60 suction stroke of the piston within the engine cylinder. This air is then compounded and forced from the pump upon the next compression stroke of the engine piston. Located in the connection between the pump 65 cylinder and the engine cylinder is a valve which I term the "breather valve." This valve is adapted to supply fresh air to the engine cylinder upon the suction stroke of the piston therein. Certain cushioning devices are provided to prevent pounding of 70 the pistons within the pump cylinders.

These and other features of the device of my invention are described in detail in the following description and are illustrated in 75 the accompanying drawings, in which:

Figure 1 is a longitudinal sectional view of the device of my invention, and Fig. 2 is a side elevational view thereof, illustrating the same in operative position upon the cylinder of an internal combustion engine.

Similar reference numerals refer to similar parts throughout the several views.

At 3 I have shown the main pump cylinder, within which is disposed a pair of reciprocating pistons indicated at 4 and 5 respectively. Each of the pistons 4 and 5 is provided with a suitable piston ring, as shown. Each of the pistons 4 and 5 is provided with an annular flange, which flanges 80 are illustrated at 6 and 7 respectively. Having one end threading into each of said flanges is a drawn tube 8 which rigidly connects the said pistons. The tube 8 is preferably provided with a closed bottom, as 85 shown, in order that it may be unnecessary to secure an absolutely airtight joint between the lower end of the tube and the flange 6 of the piston 4. The upper end of the tube 8, however, is preferably sweated 90 within the flange 7 of the piston 5 in order that the connection therewith may be absolutely airtight.

The cylinder 3 is provided with a suitable cap 9 and the bottom 10, both of which are 100 threaded in position, as clearly illustrated. Threaded into the cap 9 is a hose connection 11. Threaded into the lower portion of the hose connection is a tube 12, which projects down through an aperture in the piston 5 105 into the tube 8. The piston 5 is provided with suitable packing rings 13, which form

an airtight connection between the piston 5 and the tube 12, these rings 13 being securely held in position by means of rivets 14, which clamp said rings 13 between an 5 annular ring 15 and a ring 16 threaded into the piston 5.

The tube 12 at its lower end is provided with a suitable piston comprising a cup leather 17 retained in position by means of 10 threaded rings 18 and 19, as shown. At its lower end the tube 12 is provided with a valve seat 20, which is provided with a suitable ball 21, held against said seat by means of a spring 22 carried by a rod 23 15 threaded into the top of the hose connection 11 and extending down through the tube 12. The rod 23 is provided with suitable lugs 24 for centering the rod 23 within the tube 12 without at the same time in any way preventing 20 the passage of air through the tube 12.

The piston 5 is provided, near the periphery thereof, with a boss 25, which is integral with the annular flange 7. The boss 25 is 25 provided with a transverse bore 26 communicating with the inside of the drawn tube 8 above the piston within said tube, said bore being closed at its outer end by means of a suitable plug 27, as shown. The 30 lower piston 4 is provided with a boss 28 corresponding to the boss 25 of the piston 5. The boss 28 is provided with a bore 29, the inner end of which communicates with a hollow central boss 30 with which the piston 4 is provided, the outer end of the bore 35 29 being closed by a suitable plug 30', as shown.

Extending between the bosses 25 and 28 is a hollow tube 31 which is held in position at 40 either end by means of a solderless airtight joint comprising a tapered brass ring 32 and a nut 33 threaded within its corresponding boss, which forces said brass ring 32 around the tube 31.

45 The hollow central boss 30 of the lower piston 4 is provided with a suitable valve seat and a ball normally held seated by means of a spring 34 which acts between said ball and a plug 35 threaded into the 50 piston 4, the said spring being preferably disposed around a reduced portion of the plug, as illustrated.

The bottom 10 is provided with a central boss 36 provided with a longitudinal bore 55 therethrough having communication with the inside of the pump cylinder 3. Located within the boss 36 is a breather valve comprising a valve member 37 normally held seated by means of a spring 38, as shown. 60 Carried by the lower end of the boss 36 or stem, as it is sometimes called, is a section of pipe 39 adapted to be threaded into the ordinary spark plug opening of a cylinder of an internal combustion engine. The bottom 65 of the pump cylinder 3 is provided with

an opening registering with the longitudinal opening through the boss 36. Near the top thereof the cylinder 3 is provided with a plurality of apertures 40, the purpose of which will be presently explained.

The operation of the device of my invention is as follows: Upon the compression stroke of the piston within the engine cylinder with which the device is associated, air passes through the stem into the cylinder 3, below the cylinder 4, air at the same time passing past the valve in the hollow boss 30 of the piston 4 and passing through the hollow tube 31 into the tube 8 above the piston therein. As the connected pistons 4 and 5 move upward, due to compression within the engine cylinder, the space between the bottom of the tube 8 and the piston therein becoming less, the air between the bottom of the tube and the piston is compressed and forced past the ball check valve 21 and out of the pump through the tube 12 and hose connection. As the piston 5 approaches the top of the cylinder 3, the air between the piston 5 and the top of the cylinder escapes through the apertures 40 until the piston 5 has passed the apertures, whereupon an air cushion is formed, thus preventing the piston 5 from pounding the top of the pump cylinder. Upon the suction stroke of the piston within the engine cylinder pure air at atmospheric pressure is admitted to the engine cylinder through the breather valve in the stem of the device, the connected pistons 4 and 5 being at the same time moved toward the bottom of the cylinder 3. As this operation takes place the previously compressed air above the piston in the tube 8 passes the cup washer 17, thus passing into the space between the bottom of the tube 8 and the piston within said tube. Upon the next upward movement of the pistons 4 and 5 this air is compounded and passes out of the pump through the tube 12. As the piston 4 approaches the bottom of the cylinder 3, the hollow boss 30 entering the aperture in the bottom of the cylinder 3 shuts off to a large degree communication between the cylinder 3 and the pump stem, thus forming an air cushion which prevents the piston 4 from pounding the bottom of the cylinder 3.

The operation above described may be continued as long as the operation of the piston within the engine cylinder is continued.

What I claim and desire to secure by Letters Patent of the United States is:

1. In an apparatus for compressing air 125 which is adapted to be operated by the alternate suction and compression created within an internal combustion engine cylinder, the combination with a cylinder adapted to be connected with the engine cylinder, 130

- a piston within said cylinder, a movable compression chamber carried by said piston, a stationary piston for said movable compression chamber, and a valved passage whereby air admitted to said cylinder to operate the movable piston therein is passed to said compression chamber behind the piston therein and thence around said piston upon the next downward movement of said compression chamber.
2. In an apparatus for compressing air which is adapted to be operated by the alternate suction and compression created within an internal combustion engine cylinder, the combination of a pump cylinder adapted to be connected with the engine cylinder, a pair of connected pistons movable within said pump cylinder, a tube connecting said pistons and constituting a compression chamber, a stationary piston within said compression chamber, and a valved passage whereby air admitted to said pump cylinder to operate the connected pistons therein is passed to said compression chamber behind the pistons therein and thence around said piston upon the next movement of said connected pistons impelled by the suction created within the engine cylinder.
3. In an apparatus for compressing air which is adapted to be operated by the alternate suction and compression created within an internal combustion engine cylinder, the combination of a pump cylinder adapted to be connected with the engine cylinder, a movable piston within said pump cylinder, a movable compression chamber carried by said movable piston, a stationary piston for said movable compression chamber, and a passage whereby air admitted to said pump cylinder to operate the piston therein is passed to said compression chamber on the low compression side of the stationary piston therein and thence to the high compression side of said piston upon the next movement of the compression chamber impelled by the suction created within the engine cylinder.
4. Apparatus for compressing air comprising in combination an internal combustion engine cylinder, a pump cylinder of uniform bore, a pair of spaced pistons arranged to be reciprocated within said cylinder, a tube rigidly connecting said pistons, said tube constituting a compression chamber, a stationary piston fixed to the pump cylinder and disposed in said compression chamber, means for establishing connection between the pump cylinder below one of the pistons therein and the internal combustion engine cylinder whereby said connected pistons are reciprocated by the alternate suction and compression created within the engine cylinder, a valved passage through which air admitted to said pump cylinder to operate said pistons is passed to the compression chamber on the low compression side of the stationary piston therein, during a stroke of said connected pistons impelled by the compression created within the associated engine cylinder, said stationary piston comprising a cup-washer whereby air is arranged to pass around said stationary piston when said movable pistons are retracted by the suction created within the engine cylinder.

In witness whereof, I hereunto subscribe my name this 11th day of April A. D., 1913.

STEPHEN G. SKINNER.
